UNITED STATES PATENT OFFICE.

HEMAN A. ASHLEY, OF SPRINGFIELD, OHIO, ASSIGNOR TO WM. RIDENOUR
AND MAHLON K. BISER, OF SAME PLACE.

IMPROVEMENT IN HAY AND COTTON PRESSES.

Specification forming part of Letters Patent No. 37,370, dated January 6, 1863.

To all whom it may concern:

Be it known that I, HEMAN A. ASHLEY, of Springfield, in the county of Clark and State of Ohio, have invented a new and useful Improvement in Hay and Cotton Presses; and I do hereby declare the following to be a full, clear, and exact description thereof, reference being had to the accompanying drawings, making part of this specification.

My improvement relates, first, to a provision whereby the operations of advancing and retracting the piston or pistons may be accomplished by a continuous and nearly uniform movement of the team; second, to a provision for enabling both doors of the press to be simultaneously thrown open for tying.

Figure 1 is a perspective view of my windlass. Fig. 2 is a top view of both windlass and press. Fig. 3 is a longitudinal section of the same. Fig. 4 is a transverse section through the windlass.

A is a frame, having two similar boxes, B B', for receiving and confining the article to be compressed. C are solid ends to said boxes.

D is the feed-door.

E E' E'' are the doors which are thrown open for the purposes of tying and liberating the compressed bale.

F F' are two hooks, hinged to the frame at f' and f'', respectively, and to each other by a joint, f.

A' is an extension of the frame, and carries a vertical driving-shaft, G, having a spur-wheel, H, which is made to mesh into one or other pinion I or I' of windlass J or J' by means of a lever, K, according to whether it

is desired to apply the power to pressing or retracting. The windlass J connects by cords L with sheaves M in toggle N and in the frame A. The toggle N is hinged at its extremities to pistons O O'. By the above-described arrangement of mechanism a great and gradually-accumulative pressing power is obtained. The windlass J' connects by cord L' directly with the pistons O and O', enabling said windlass to act with a uniform and rapid motion to retract said pistons. It will be seen that the two windlasses wind always in the same direction, but never at the same time, and that the winding up of either acts to unwind the other by simply drawing on its cord. The pressing being completed, a sharp blow or kick by the operator upon the hinge f of the duplex hook F F' acts to release both of the side doors at once.

I claim herein as new and of my invention—

The arrangement of windlasses J J', lever K, pinions I I', spur-wheel H, and cords L L', attached or connected, respectively, to the toggle M N and directly to the pistons in the manner and for the objects stated, when combined with hooks F F', hinged to each other and to the frame, and adapted to open and close both doors E E'' at once, in the manner set forth.

In testimony of which invention I hereunto set my hand.

HEMAN A. ASHLEY.
